J. N. D. BROWN.

RAILWAY ROAD BED, TRACK, AND RAIL CONSTRUCTION.

APPLICATION FILED JULY 13, 1911.

1,009,020.

Patented Nov. 14, 1911.

UNITED STATES PATENT OFFICE.

JOHN N. D. BROWN, OF ANADARKO, OKLAHOMA.

RAILWAY ROAD-BED, TRACK, AND RAIL CONSTRUCTION.

1,009,020.

Specification of Letters Patent. Patented Nov. 14, 1911.

Application filed July 13, 1911. Serial No. 638,272.

To all whom it may concern:

Be it known that I, JOHN N. D. BROWN, a citizen of the United States, residing at Anadarko, in the county of Caddo and State 5 of Oklahoma, have invented new and useful Improvements in Railway Road-Beds, Tracks, and Rail Construction, of which the following is a specification.

My invention relates to railway road-bed, 10 track and rail construction; and the object of the invention is to adapt a reinforced concrete road-bed and track construction with a continuous cushion to use with the present form of rail; to provide means for 15 securing the rails together and holding them in gage without the use of wood ties; to provide means for anchoring the rails to the concrete rail-bases; and further, to provide means by which the rails and cushions can 20 be removed and replaced without injuring or destroying any other part of the construction, and means by which the bolts and nuts used in the construction can be securely locked in position; the arrangement and 25 construction being hereinafter clearly set forth and specified.

Figure 1 is a vertical cross-sectional view of the road-bed, track and rail construction. Fig. 2 is a modified form of Fig. 1 in 30 which ballast is used between the rails in place of concrete, with other minor changes in the construction. Fig. 3 shows the rail and cushion in elevation. Fig. 4 shows the rod that connects the parallel reinforced-concrete rail-bases. The rail anchors pass 35 through the eyes or loops in the ends of this rod. Fig. 5 shows the lower part of the combined tie-rod and connected rail-chairs. Fig. 6 shows the pattern of steel-reinforcing-bar recommended. Fig. 7 is a lineal vertical-section through the center of the end 40 of Fig. 5 showing the rail-base resting thereon. Fig. 8 is a cross-section of the end of tie-rod 19 at the point where the nut-lock-wire passes through it. Fig. 9 is a 45 cross-section in the center of the nut of fish-plate bolt showing the wire-nut-lock in position. Fig. 10 is a lineal cut through the center of a bolt showing a modified wire-nut-lock. Fig. 11 is a lineal section through 50 the center of a common rod coupling.

Like numerals represent like parts of the construction.

1 is the rail—the same pattern as that now in general use. 55

2 is the bolt that connects the rail and rail tie-rod.

3 represents the hole that is placed near the end of the tie-rod; a slot in one side of bolt 2 corresponding to this hole provides a 60 passage for the wire-nut-lock; compressible lead washers of varying thickness are used to bring the hole in the rod or nut in register with the slot in the bolt; a mark on the head of bolt and nut shows when the 65 hole and slot are in line.

4 represents the enlarged ends of tie-rods that receive bolts 2.

5 represents the widened ends of the lower part of the combined tie-rods and rail-chairs. 70

6 represents the lip that is turned up at the ends of rail-chairs.

7 represents the part of rail-chairs, cut from the same and turned up and formed for a clamp for the inside of rail-base. 75

8 represents the combined tie-rod and connected rail-chairs; these parts, upper and lower (19 and 9) are welded together where they join, forming a single part of the construction.

9 represents the rod connecting the rail-chairs 5. 80

10 represents the rod (Fig. 4) that connects the concrete rail-bases and by means of the eyes in the ends of the same, prevents 85 the splitting of the concrete by the wedge shaped keys 23 that pass through said eyes.

11 represents the bolt, with an eye at one end (same as 33) and a washer and nut at the other end, that takes the place of rod 90 10 in Fig. 1 and prevents the wedge shaped key from splitting the concrete base.

12 represents the ordinary fish-plate used, in the present rail construction.

13 is the nut on the fish-plate bolt. 95

14 represents the wire-nut-lock in position—bent down so it cannot work out—nor can the nut turn or work loose. Compressible lead washers of slightly varying thickness are used, when necessary, back of 100 the nut or head of the bolt to bring the hole in the nut and the slot in the bolt in line and register.

15 represents a mark (made with a file or cold chisel) on the end of the bolt showing 105 the position of the slot.

- 16 represents a mark on the head of bolt 2 showing the position of the slot in the bolt.
- 17 represents nonconnected rail-chairs 5 placed at intervals between the combined and connected rail-chairs and tie-rods.
- 18 represents the space (three-eighths of an inch) between the base of the rail and the cushion.
- 10 19 represents the tie-rod which, in combination with the rail-chair rods 9 to which it is united and a part of, clamps the rails together and holds them in gage. This member or members would be manufactured 15 of the proper length, taking into consideration the thickness of the web of the rail and the width of the base of the particular weight of rail to be used, to bring the rails in gage when bolted snugly up.
- 20 20 represents anchor bolts of three-quarters of an inch round iron or steel with the upper end flattened wedge shape and turned as shown to form a clamp or anchor for the rail. These anchors should be placed at intervals of from four feet to eight feet.
- 25 21 represents a plate, some three inches square, embedded in the concrete and forming a nut and anchor for bolt 20.
- 22 represents an anchor plate of sufficient 30 length to pass under three of the lineal reinforcing bars 25 and form an anchor for bolt 20. Bolt 20 would thus clamp the rail and reinforcing bars 25 together.
- 23 represents a wedge shaped key made 35 from three-quarters of an inch round iron or steel and formed as shown. The purpose of this key is to hold anchor bolts 20 up snugly to the rail base; to prevent anchor bolt 20 from turning after it is screwed 40 down tightly into anchor plate 21 or 22; and, by passing through the eye of bar 10 or bolt 11, to clamp the concrete together and prevent its splitting or cracking.
- 24 is a three-eighths of an inch steel reinforcing bar.
- 45 25 represents three-quarters of an inch steel reinforcing bars.
- 26 represents the nut and washer on bolt 11.
- The metal forming member 7 (see Figs. 5 50 and 7), instead of being a separate piece welded on the rail-chair, is cut loose, at one end and both sides (leaving the other end attached) from that part of the chair or plate that is covered by the base of the rail, 55 and then turned up at a right angle to the plate and then forward in a suitable manner to engage the base of the rail. 27 represents the place from which the metal is cut.
- 28 represents half circle depressions 60 formed at intervals in the cushion for the purpose of drainage should the rail-chairs be forced down into the cushion until the base of the rail rests on the same.
- 29 represents conduits for wires used in 65 railway operation.
- 30 represents the continuous cushion of asphalt, sand and oil, or other materials hereinafter specified.
- 31 represents ordinary concrete—crushed stone, sand and cement.
- 32 represents ordinary railway ballast—crushed stone, gravel, cinders or burnt clay.
- 33 represents the loop or eye formed in the end of rod 10.
- 34 represents thin washers placed under 75 bolt heads or nuts to bring the hole and slot of bolt and nut in register.
- 35 represents a plate or chair two feet long placed under rail joints.
- 36 represents a lineal slot cut in the 80 threaded end of a bolt to receive the nut-lock-wire.
- 37 represents a hole drilled or punched through one side of a nut to receive the nut-lock-wire.
- 38 is a common rod coupling.
- To install my construction, I would provide that the parallel trenches required be dug ten to fifteen inches deep according to the character of earth road-bed and the requirements of the construction, and that the bottom of the trenches be well tamped, and, if the road-bed is soft and spongy, that the trenches be dug deeper and the deeper part filled with dry clay or broken stone; that 90 when so dug plank of the proper width be provided in sufficient quantity for one day's construction, and that half inch holes be bored in the plank one-half inch deep and one and one-half inches from the bottom of 100 the same, and at intervals of four feet; and that steel reinforcing bars 24 be cut to seventeen inch lengths, and placed in the above described holes after the planks are set in the trenches, and earth packed against the 105 bottom of planks on the outside. The planks provided for the inside of trenches should be in two widths, one to come up to the bottom of rod 10 or bolt 11 and the other to complete the width same as the outside 110 planks; notches in the upper piece would fit over rod 10 or bolt 11. Place braces cut to sixteen inch lengths, and with a notch in one side to hold anchor bolts 20 in position, near the top of the parallel planks and wire the 115 planks together at these points. Line and level up the forms thus made to correspond to grade of road-bed and gage of rails and see that anchor bolts 20 with their accompanying wedge shaped key are in proper position to engage the rail bases. When the forms are complete and secured in position with lineal reinforcing bars 25 and rods or bolts and anchors and anchor keys properly placed and secured, proceed to fill the forms 120 with a good quality of concrete; and before the forms are full, place cushions 30 or wood forms of the same shape in position, cut a circular notch in the same where the anchor bolts 20 come. After properly placing the 125 130

cushion or its form, finish the concrete and trowel up smoothly on top and around the edges of the cushion. After the concrete has sufficiently hardened remove the forms and carry forward for additional use.

As an aid in placing the anchor-bolts 20 in the proper position, I would use a frame or form composed of three-quarter inch by four inch strips, from sixteen feet to twenty-four feet long secured together by similar strips, at a distance corresponding to rail-bases when rails are properly set and gaged. I would brace this frame thoroughly so that the long parallel strips would remain straight and rigid. After the frame is properly constructed and braced, cut the cross strips in two in the exact center of frame and hinge them together. Place the center of this frame in line with the tracks in the center stakes of earth road-bed and the outer parts of the frame on top of the inner plank of concrete rail-base forms and place anchor bolts 20 at suitable intervals along the outside of this frame. Raise the frame in the center and slide it forward and place in position for the location of additional anchor bolts.

When the steel-reinforced-parallel rail-bases have thoroughly set proceed to place the cushion, if it was not placed when constructing the same, and put the combined tie-rods and connected rail-chairs in position, with the nonconnected rail-chairs at intervals between them, and proceed to place the rails in the usual manner; put the long rail-chairs 35 under rail joints; place fish-plates and bolt in position; insert and tighten up bolts 2 and screw down anchor bolts 20. As the construction train backs down tighten up the anchor-bolts before placing key 23.

To avoid any possible chance of bolts or nuts working loose, I would use bolts or nuts made and adapted to the use of a nut-lock-wire, as shown by drawings herewith.

In Fig. 1 I have shown concrete between the rails, while in Fig. 2 ordinary ballast is provided for. The concrete between the rails or the ballast can be placed at any time after the road is in operation.

The cushion 30 should be composed of asphalt, sand and crude oil or oil residuum, substantially the same as that used for the finishing coat of asphalt pavement; this mixture should be pressed or rolled sufficiently dry and firm, so that it would not become soft or mobile under a temperature of one hundred and ten degrees; dry sawdust saturated with oil may be used in the asphalt mixture in place of sand; or small wood fiber (the size of wheat straw) saturated with oil and tied in small bundles may be used in combination with the asphalt, sand and oil mixture; or wood or vegetable pulp saturated with oil as above may be used;

or light porous wood free from knots or hard pitchy spots may be kiln dried and boiled in crude oil and used for the cushion; or any other resilient material suitable for such a purpose may be used.

I provide, in case it is desired to so construct that the cushion can be removed and renewed at some future time, that common rod-couplings be placed in rod 9 near the rail-chairs.

I provide and claim the right to vary the size of the steel reinforcing bars, tie-rods, rail-chairs, anchors, anchor bolts, anchor keys and bolts and the intervals at which they are placed; the thickness, width and depth of the concrete and any other matters essential to the adaptation of my construction to the weight and size of different rails, the make of different railways and differing local conditions.

Having thus described my invention of a comparatively permanent railway structure, without the necessary use of wood or other perishable materials, adapted to use the common form of rails, requiring the use of little additional steel except as reinforcing for the concrete; and provided a simple means for the rapid exchange of rails and cushions without disturbing or injuring the concrete structure, what I claim and desire to secure by Letters Patent is clearly set forth in the following claims numbered one to eleven inclusive:

1. A railway road-bed, track and rail construction in combination with concrete rail-bases reinforced lineally by parallel steel reinforcing bars wired to short lateral reinforcing bars placed near the bottom of said concrete rail-bases and by conduits placed near the top and outside of said bases; as and for the purpose shown and specified. 100

2. A railway road-bed, track and rail construction in combination with steel reinforced concrete rail-bases of the class shown, specified and claimed united and reinforced laterally by steel reinforcing and tie-rods and united and connected by concrete extending continuously between the rails, said central concrete reinforced laterally by tie and gage rods united to the connecting rods of opposing rail-chairs; as and for the purpose shown and specified. 110

3. A railway road-bed, track and rail construction in combination with concrete rail-bases of the class shown, specified and claimed steel reinforced laterally and lineally; with anchor plates, having a threaded hole in the same, placed, at intervals, in contact with the lineal reinforcing bars near the bottom of the concrete rail-bases; with anchor bolts of round metal with lower ends threaded and upper ends, commencing above the threaded part, flattened on one side and turned at the top, from the flattened side, at a suitable angle to engage the bases of the 120 125 130

4 rails; with anchor bolts engaging the bases of the rails and extending down through the concrete rail-bases and screwing into anchor plates placed near the bottom of the same thus clamping the rails to the concrete rail-bases; with wedge shaped anchor keys, round on one side and flat on the other side with upper ends turned at a suitable angle, extending down into the concrete, with the flat sides in contact with the flat sides of the anchor bolts and held snugly thereto by the concrete and by the ends of the metal reinforcing and tie-rods through which they pass; as and for the purpose shown and specified.

5 4. A railway road-bed, track and rail construction in combination with parallel steel reinforced concrete rail-bases; with cushions of resilient material embedded, continuously, within and upon concrete rail-bases reinforced by parallel steel reinforcing bars wired to short lateral steel reinforcing bars placed near the bottom of the concrete bases; with resilient cushions having half-circle depressions formed at intervals in the top of the same to provide drainage for that part of the road-bed lying between the rails; as and for the purpose shown and specified.

10 5. A railway road-bed, track and rail construction in combination with continuous rail cushions supported by parallel concrete rail-bases reinforced lineally by parallel steel reinforcing bars wired to lateral reinforcing bars placed near the bottom of the same; with connected opposing rail-chairs supported by cushions of resilient material; with opposing rail-chairs formed from oblong steel plates with the outer end turned up at a right angle to receive the outer edges of the bases of the rails and a strip of the metal cut loose, at the outer end and both sides from that part of the rail-chair upon which the rails rest, and turned up and then forward in a suitable manner to receive and secure the inner edges of the bases of the rails; with opposing rail-chairs joined together and held in gage by a metal rod united to and connected with a metal rail-gage and tie-rod and welded to the inner ends of the opposing rail-chairs; as and for the purpose shown and specified.

15 6. A railway road-bed, track and rail construction in combination with concrete rail-bases steel reinforced lineally and laterally by steel reinforcing bars placed near the bottom of said rail-bases; with resilient cushions supported by reinforced concrete rail-bases; with connected opposing rail-chairs placed at suitable intervals on resilient continuous cushions; with non-connected rail chairs placed at short intervals between connected opposing rail-chairs to furnish additional and closer supports for the bases of the rails; with rails of the common form and pattern resting on connect-

ed and non-connected rail-chairs, the inner edges of the bases of the rails secured by the connected rail-chairs and the outer edges of the bases securely anchored to the reinforced concrete sub-structures by suitable anchor bolts; with reinforcing tie-rods placed in the concrete rail-bases, immediately under the cushions carried by the same, and extending laterally from one anchor bolt to an opposing anchor bolt and which, by means of the eyes in the ends of the same through which the anchor bolts and anchor keys pass, hold the anchor bolts up snugly to the rail-bases and prevent the same turning therefrom; with anchor bolts and anchor keys so constructed and placed that by pulling out the anchor keys and turning the anchor bolts a quarter turn the outer edge of the base of the rail is released; as and for the purpose shown and specified.

20 7. The combination, in railway road-bed, track and rail construction, of parallel concrete rail-bases steel reinforced lineally near the bottom of the same by parallel steel reinforcing bars wired to short lateral reinforcing bars; with cushions of resilient material embedded, continuously, in reinforced concrete rail-bases; with connected and non-connected rail-chairs resting upon continuous resilient cushions; with rails of a usual form and pattern resting on rail-chairs supported by continuous cushions of resilient material; with opposing rails bound together and held in gage by combined tie and gage rods united to rods connecting and holding in gage opposing rail-chairs; with combined reinforcing tie and gage rods with threaded holes in the center of the enlarged ends where they abut against the webs of the opposing rails, with suitable bolts to pass through holes in the webs of the rails and screw into the threaded holes in the enlarged ends of the combined tie and gage rods, securing and clamping the rails to the rods; with tie and gage rods united to and a part of tie and gage rods connecting opposing rail-chairs, which combination of rods and rail-chairs unites and holds in gage the opposing rails; with anchor bolts of suitable design and length placed, at intervals of reasonable length, on the outside of the cushions to clamp, secure and unite the rail structure to the reinforced concrete sub-structures; as and for the purpose shown and specified.

25 8. The combination, in railway road-bed, track and rail construction, of parallel concrete rail-bases steel reinforced near the bottom by lineal reinforcing bars wired to short lateral reinforcing bars; with connected opposing rail-chairs, resting upon continuous cushions of resilient material, connected by combination metal rods with common rod-couplings provided to place in said rods.

30 95 100 105 110 115 120 125 130

near the rail-chairs to adjust the gage of the bases of the rails and cant the rails, slightly, toward the center of the track, when desired to so construct, and to provide means for 5 moving the connected rail chairs without disturbing the central concrete and by the use of said rod-couplings providing a means for changing the cushions when perishable materials are used for the same; as and for the 10 purpose shown and specified.

9. A railway road-bed, track and rail construction in combination with continuous parallel concrete rail-bases steel reinforced lineally and laterally near the bottom of the 15 same to prevent the pulling apart or cracking of the concrete when subject to the strain of heavy traffic; with suitable cushions continuous with the concrete rail-bases to provide necessary resilience for the steel rails 20 and retard the tendency to crystallization of the steel and to prevent the gradual disintegration of the concrete structure by the impact and oscillation of heavy traffic; with suitable means to prevent the spreading of 25 the rails by the gradual loosening of nuts or bolts, bolts securing the rails to the tie-rods having a half circle slot across the threaded ends of the same, the enlarged ends of the tie-rods having a lateral hole through one 30 side of the same corresponding to the slot in the bolts, a nut-lock wire being provided to pass through the hole in the rod and engage the slot in the bolt, thin compressible lead washers being provided to use under 35 the heads of the bolts to bring the hole in the rod and the slot in the bolt in line and register; as and for the purpose shown and specified.

10. A railway road-bed, track and rail 40 construction in combination with concrete rail-bases, steel reinforced lineally and laterally near the bottom of the concrete, resilient continuous cushions carried thereby, connected and non-connected rail-chairs 45 resting on said cushions, rails of a common form and pattern resting on said rail-chairs and connected at their abutting ends in the usual manner except as to the fish-plate

bolts, these bolts with their accompanying nuts being adapted to the use of a nut-lock 50 wire, the threaded ends of the bolts having a half circle slot across the same while the accompanying nuts have a corresponding hole transversely through the same, a nut-lock wire passing through the hole in the 55 nut and engaging the slot in the bolt prevents the nut from turning or working loose, thin metal washers of slightly varying thickness and a compressible lead washer are used; when necessary, to bring the hole 60 in the nut and the slot in the bolt in line and register; as and for the purpose shown and specified.

11. A railway road-bed, track and rail construction in combination with concrete 65 rail-bases reinforced lineally by parallel steel reinforcing bars wired to short lateral reinforcing bars placed near the bottom of said concrete rail-bases, by conduits placed near the top and outside of the concrete bases 70 and by steel rails imposed upon rail-chairs resting on resilient cushions at the top of said concrete bases and securely anchored and clamped thereto; with modified fish-plate bolts to secure the abutting ends of the 75 rails together, said bolts having a lineal U-shaped slot in the threaded ends of the same and holes in their accompanying nuts extending into the threads and of a size corresponding to the lineal slots in the bolts 80 and a malleable nut-lock wire provided to enter the hole in the nut and bend and follow the slot in the bolt locking the nut on the same, thin compressible lead washers are used under the head of the bolts to bring the 85 slot and the hole in register; said nut-lock wire, when of suitable size and malleability, can be quickly and easily removed by forcing it down through the nut and out through the slot in the bolt or by pulling it back through 90 the nut; as and for the purpose specified.
